(57) CLAIM

The ornamental design for a shoe with religious text, as shown and described.

DESCRIPTION

FIG. 1 is a right side view of a shoe with religious text, showing my new design;

FIG. 2 is a left side view thereof;

FIG. 3 is a front view thereof;

FIG. 4 is a rear view thereof;

FIG. 5 is a top view thereof;

FIG. 6 is a front right perspective view thereof;

FIG. 7 is a front left perspective view thereof;

FIG. 8 rear right perspective view thereof; and,

FIG. 9 rear left perspective view thereof.

FIGS. 1 through 9 illustrate a left-footed shoe with religious text, it is to be understood that the invention includes a right-footed shoe with religious text which would be illustrated as a mirror image of any or all of the views shown in FIGS. 1 through 9.

The undisclosed portions of a sole of the shoe with religious text form no part of the claimed design.
